UNITED STATES PATENT OFFICE.

JOHN J. CRAVEN, OF PATCHOGUE, NEW YORK.

REFRIGERATING APPARATUS FOR CHAMBERS AND BUILDINGS.

SPECIFICATION forming part of Letters Patent No. 300,695, dated June 17, 1884.

Application filed April 4, 1884. (No model.)

To all whom it may concern:

Be it known that I, JOHN JOSEPH CRAVEN, a citizen of the United States, residing at Patchogue, in the county of Suffolk and State 5 of New York, have invented new and useful Improvements in Refrigerating Apparatus for Chambers and Buildings, of which the following is a specification.

The object of my invention is to secure a thorough refrigeration or cooling of a compartment for the purpose of preserving perishable articles placed therein, using as the cooling medium ice and salt and the meltage therefrom with good advantage and economy. In 15 this I aim to get all the cooling properties that may be obtained by the combination of ice and salt employed in two distinct and separated bodies—one solid and the other a liquid resulting from the solid—through and in 20 contact with which air is forced under pressure, and delivered in a blast into the apartment, so as to maintain therein a continuous and uniform cold condition. Both these cooling bodies are contained within the cold-producing 25 chamber, but separated, so as to prevent the contact of the liquid with the solid, by an intervening air-space and an overflow, because were these bodies in contact they would 30 form a compact stratum of ice at their junction and prevent the passage of the air through the cold-producing chamber. It is this complete 35 separation of the ice and the resulting meltage therefrom that enables me to utilize the cooling properties of these two separate bodies by first forcing a current of air through the liquid and then in contact with the ice and salt, so that both are used to their fullest cooling capacity upon the same forced volume of air. In the passage of the air through these separate 40 cooling bodies provision is made for diffusing it in separate streams, the better to increase its coldness. Provision is also made for sealing the supply-hopper to prevent the entrance of air into the cold-producing chamber when 45 filling it with ice, and thereby prevent disturbance or interruption of the air-blast from the cold-producing chamber to the refrigerator. Provision is also made whereby the overflow from the cold-producing chamber is utilized 50 to cool the air before its entrance into the blower, thereby obtaining cooling results by the entire body of ice and the meltage there-

from. These and other matters of construction and of combinations I will now proceed to describe preparatory to a specific designation of the parts and combinations which constitute my invention.

Referring to the accompanying drawings, Figure 1 represents in perspective a refrigerating apparatus embracing my invention; 60 Fig. 2, a vertical section through the cold-producing chamber and the air-inlet pipes, and Fig. 3 a horizontal section of the same.

The apparatus is designed for maintaining a low degree of temperature in chambers or 65 compartments for the preservation of perishable articles.

The refrigerating compartment or chamber A is constructed in any suitable manner for the purpose, and is provided with suitable 70 entrance-doors. The refrigerating apparatus is outside of the refrigerator proper, and consists of an air-tight cold-producing chamber, B, constructed to hold brine and ice in two separated and distinct bodies, into which the 75 air to be cooled is forced, and from which it is delivered by a pipe, C, in a blast into the refrigerator. Into this cold-producing chamber the air is delivered by a pipe, D, preferably passing through its top, and extending 80 to near its bottom, where it delivers the air. This chamber is divided horizontally by a perforated partition, a, upon which the ice rests, and partially fills the upper portion of said chamber.

About the delivery end of the air-conduit D, and near the bottom of the chamber, a perforated diaphragm, b, is placed, and below the partition a this chamber receives and holds the meltage from the ice and salt above. An 90 overflow-pipe, c, connects with this chamber at a point below the partition a, so that the liquid is prevented from rising to said partition, and there is therefore an air-space, d, always between the surface of the liquid and 95 the partition, so that the body of the ice can at no time come in contact with the body of the liquid, for in such a contingency a solid stratum of ice would be formed at their junction and prevent the passage of the air through 100 the liquid. The cold-producing chamber is supplied with salt and ice in a broken condition by a hopper, E, which is provided with a sealed cover, e, and slide f, whereby the

hopper can be first filled and sealed and the inner slide opened to allow the charge to be dropped within the chamber without interrupting the refrigerated air-current in its passage to the preserving-compartment.

5 The blower F is closed and connected to the pipe D, into which it delivers the blast, while it receives the air through a pipe, G, which passes into and through a closed tank,

10 H, into which the overflow-pipe c terminates, is sealed, and by which it is kept filled with the brine overflowing from the cold-producing chamber. This tank has an overflow-pipe, I, through which the brine escapes, and the air-15 inlet pipe G opens outside of said tank, so that the air drawn through this pipe is partially cooled before it enters the blowers by the cold resulting from the overflow from the cold-producing chamber.

20 The cold-air pipe may enter the preserving-chamber by a single opening, or by several branch pipes, and the air is delivered therein in a blast. As the preserving-chamber is made tight, provision is made for ventilating it 25 and relieving it from the pressure of the cold-blast by one or more valved openings, g; but my object is to keep the preserving-chamber under some degree of pressure in order to secure a general dissemination of the cold blast 30 therein. As the air is delivered into the cold-producing chamber immediately below the perforated bottom diaphragm, b, the latter serves to break up the volume and diffuse it through the body of the liquid, thus bringing

35 it more intimately in contact with the cold liquid. Leaving the body of the liquid, the blast passes through another perforated diaphragm or partition, a, by which it is again diffused through the body of ice and salt supported thereon, and delivered to the preserving-chamber through the pipe C, which opens 40 into the top of the cold-producing chamber.

In the drawings I have shown the side of the cold-producing chamber removed, and also 45 the top of the supplemental air-cooling tank, to expose the interior construction of these parts. The pipe D must extend below the perforated partition a; but I prefer to terminate it below the perforated diaphragm, so 50 that it passes into the chamber through the body of the ice, and terminates within the body of the liquid.

55 From the foregoing it will be seen that a preserving-chamber can be kept at a low degree of temperature by air continuously forced into a body of liquid resulting from the melting of ice and salt, diffusing the air-blast into separate streams as it is forced through said liquid refrigerant, and then in separate 60 streams in contact with a body of ice, between which and the refrigerating-liquid the confining-chamber of the latter has a sealed overflow, to maintain the separation of the solid and liquid refrigerants.

65 I claim—

1. For the purpose of refrigerating a preserving-chamber, the combination, with said

chamber, of a closed cold-producing chamber containing a solid refrigerant above and separated from a liquid refrigerant, an overflow-pipe entering said chamber into an air-space separating the solid and the liquid refrigerants, a blower delivering the air into the contained liquid refrigerant, and a pipe for delivering the cold air from said cold-producing chamber, substantially as described.

2. In a refrigerating apparatus, a closed cold-producing chamber divided by a horizontal perforated partition, and having a lower perforated diaphragm, in combination with an overflow-pipe arranged below said perforated partition, an air-induction conduit passing through said partition, terminating below the perforated diaphragm, and an air-eduction pipe, substantially as described, for the purpose specified.

3. The combination, in a refrigerating apparatus, of the closed cold-producing chamber, divided by a horizontal perforated partition, with an air-induction pipe passing through and terminating below said perforated partition, an overflow-pipe, a supplemental cooling-tank into which it terminates, and a closed blower receiving air by a pipe passing through said supplemental cooling-tank, substantially as described, for the purpose specified.

4. The combination, in a refrigerating apparatus, with a closed cold-producing chamber having an induction and an eduction air-blast pipe, of a hopper having a sealing-cover and a charge-delivering sealing-slide, substantially as described, whereby to deliver the ice-charge into said chamber without interrupting the air-current through the same.

5. The combination, with a preserving-chamber, of a connected closed cold-producing chamber containing in separate bodies a solid refrigerant above a liquid refrigerant, an overflow-pipe entering said chamber between these contained refrigerating bodies, a supplemental cooling-tank, and a closed blower having its air-supplying pipe passing into and through said supplemental cooling-tank, substantially as herein set forth.

6. A closed cold-producing chamber divided by a perforated horizontal partition, whereby a solid refrigerant is separated from a liquid refrigerant, a sealing supply-hopper, and an overflow-pipe, in combination with an air-induction, an air-eduction pipe, and a preserving-chamber, substantially as herein set forth.

7. The combination of a preserving-chamber with a closed cold-producing chamber containing a solid and a liquid refrigerant separated by an air-space, an overflow-pipe connecting with said contained air-space between the cold-producing bodies, a closed blower, and suitable inlet and discharging air-pipes, the inlet-pipe being arranged to deliver the air into the liquid body, substantially as described, for the purpose specified.

8. The method herein described of refriger-

erating a preserving-chamber, which consists in forcing air through and in successive contact with separated liquid and solid refrigerating bodies contained within the same chamber, maintaining the separation of said refrigerating bodies by an intervening air-space, and a sealed overflow to preserve them in condition for the passage of the air to be cooled, and delivering the air so cooled by its successive passage through these separated bodies into the preserving-chamber, substantially as described.

9. The cold-producing chamber B, con-

structed to hold brine and ice in two separated bodies, one above the other, and having a 15 sealed top door, e, combined with the overflow-pipe c, the separating air-space d, the blower F, and the preserving-chamber, substantially as herein set forth.

In testimony whereof I have hereunto set my 20 hand in the presence of two subscribing witnesses.

JOHN J. CRAVEN.
